UNITED STATES PATENT OFFICE.

FREDRICK JAMES SIVYER, OF EDMONTON, NEAR CAIRNS, QUEENSLAND.
AUSTRALIA.

MANUFACTURE OF COKE AND APPARATUS THEREFOR.

1,354,809.

Specification of Letters Patent.

Patented Oct. 5, 1920.

Application filed November 15, 1917. Serial No. 202,252.

To all whom it may concern:

Be it known that I, FREDRICK JAMES SIVYER, subject of the King of Great Britain and Ireland, residing at Edmonton, near Cairns, Queensland, Australia, brickmaker, have invented new and useful Improvements in the Manufacture of Coke and Apparatus Therefor, of which the following is a specification.

10 This invention relates to the manufacture of coke by the combustion of coking coal with limited access of air in closed stalls, according to the method in which the coal is carried on trucks which are loaded out 15 side the stall, when loaded wheeled into the stall, and when the charge is coked, wheeled out of the stall and the coke quenched and discharged.

In practice the stalls are built to accommodate each one truck, but they might be built to accommodate each two or more trucks.

In the accompanying drawing Figure 1 is a central longitudinal section through the 25 stall with a loaded truck inclosed therein; Fig. 2 is a perspective view of the truck body showing the detail structure of the cellular tray and cellular coamings; and Fig. 3 is an end elevation of a stall with 30 end doors closed on a loaded truck, portions of the truck body being shown in section to illustrate the structure of the tray and its coamings.

The stall consists of two side walls A and 35 an arched top B built of brickwork and suitably reinforced or stayed and structurally adapted to withstand the temperature necessary for the coking of coal within the stall. A line of rails YY is laid through 40 the stall on iron sleepers, these rails being continued at one end of the stall to the location of suitable loading appliances, and at the other end to the location of suitable quenching and discharging appliances.

45 Two stay posts VV are erected at either end of the stall and these are brace-bolted together in the manner shown for the purpose of supporting the brickwork structure and providing supports and runways for the 50 stall doors. The door and frame construction at either end of the stall is similar. A smoke flue C is constructed in the top of the arch B for discharging gaseous and vaporous products of combustion and providing

a means whereby the same may be drawn off for reduction to commercial products.

The truck O comprises an under frame on four or more wheels and a cellular tray body with fixed coamings on two ends and one side thereof, and a hinged coaming of special construction on its second side. The 60 wheels and underframe of the truck come completely within the stall, while the tray body and its side and end coamings extend to or slightly beyond the ends of the stall, 65 where it is met by the upper and lower doors of the stall, which, during the coking operation, are closed so as to exclude inlet or outlet drafts. The tray and coamings of the truck body are cellular. They are constructed 70 of iron plates framed on I-bars and channel bars; air vents are made in the outer shell plates to allow air to pass through the cellular spaces, entering at the 75 vents in the end coaming of the truck projecting beyond one end of the stall, and passing out of the vents in the end coaming of the truck projecting at the other end of the stall.

L is an outer end plate of the truck, and 80 H the tray body. E are ventilating holes serving the cellular bottom R of the tray. Air passes into the cellular bottom of the truck body through the holes E at one end thereof and hot air finds exit through corresponding holes at the other end of the truck body. The walls or coamings of the tray are similarly constructed cellularly, as 85 shown at J. Air enters the cellular coaming at one end of the tray body at K and 90 after traversing it passes therefrom through the holes G into the cellular space J in one of the side coamings. Thence it passes back through the cellular coaming at the other end of the truck, and escapes outward to 95 atmosphere by holes in the outer wall thereof, corresponding with the inlet holes K. The hinged side coaming of the truck body (M) is mounted independently of the end coamings so as to hinge outward to facilitate the discharging of the truck. The other side coaming is thus in the same cooling air circuit as the end coaming. The ends of this hinged coaming are pierced with air holes F. Air enters through them from 100 atmosphere at one end of the truck and hot air passes out of corresponding holes at the 105 other end of the truck.

The upper door N of the stall is slidable in runways in the posts V. It is moved to slide it open or closed by lines S running over sheave rollers T, and is counterbalanced by weights (not shown) hung on the ends of said lines. The lower doors P of the stall are hinged doors pintled on the lower ends of the frame V. All the doors are fitted to make a fair fit with the chamber brickwork and with the truck tray and end coamings, so that tight working joints may be made by luting with clay paste. The upper doors are cellular and are fitted with a water cooling service, the pipe connections Z (inlet) and Z' (outlet) being of flexible metallic piping.

A truck, packed with coal to its full capacity as indicated in the drawing, is run into the open stall on the rails Y and the stall doors N and PP then closed. All the door joints are luted with clay, and the luting is maintained during the burning operation so as to prevent false drafts. The charge is lighted before the doors are closed. After the doors are closed, further admission of air is regulated by the dampers U, of which any required number may be provided in the upper doors N. The outlet draft through the up-take C is also controlled by a damper therein (not shown). The doors N and PP close neatly against the under side and top side of the protruding ends and coamings of the truck body, leaving the outer faces of said ends and end coamings exposed to external atmosphere to facilitate inflow and exit of air for the cooling of the truck body. After combustion is completed and the charge has been converted to coke, the doors are opened and the truck wheeled out on the rails YY and the burning coke quenched and afterward discharged. The truck may then be refilled for another burning.

To facilitate truck handling, the rail track is either made continuous, so that the trucks may be worked in continuous circuit, or

turnouts are provided to permit trucks to be shunted to the coal recharging site after they have been discharged at the coke dumping site.

50

If the temperature of the stall after one or more burnings have been completed is sufficiently high to initiate the combustion of a fresh charge, the process may be made practically continuous without introducing fire into successive charges, by running in freshly loaded trucks as each finished truck is removed.

55

What I claim as my invention and desire to secure by Letters Patent is:—

60

1. Apparatus for burning coal to coke, comprising a stall with a gas vent formed in the upper part thereof, a rail track through said stall, a truck having an end vented cellular body overhanging the ends of its underframe, and adapted to run on said rail track, and end doors on said stall adapted to meet the body ends of said truck so as to permit said body ends to project beyond said doors and expose the cell vents therein to atmosphere.

65

2. In apparatus as set forth in claim 1, a tray body comprising an end vented cellular bottom and cellular coamings, of which the coaming at one side of said body is hingedly mounted on the tray independently of the other coamings thereon.

75

3. Apparatus for burning coal to coke comprising a closed stall provided with fire-proof doors at its ends, an end-vented cellular body truck within said stall, said doors being adapted to close upon the truck in such manner as to leave the vented ends of the body thereof exposed to atmosphere.

80

In testimony whereof I have signed my name to this specification in the presence of two subscribing witnesses.

FREDRICK JAMES SIVYER.
